UNITED STATES PATENT OFFICE.

JOHN S. WORTH AND CHARLES BRECHT, OF COATESVILLE, PENNSYLVANIA, ASSIGNEES
TO SAID JOHN S. WORTH AND WILLIAM P. WORTH, OF COATESVILLE, PENNSYLVANIA.

RAILWAY-CAR.

1,224,050.

Specification of Letters Patent. Patented Apr. 24, 1917.

Application filed December 7, 1914. Serial No. 875,917.

To all whom it may concern:

Be it known that we, JOHN S. WORTH and CHARLES BRECHT, citizens of the United States, and residents of Coatesville, Chester county, Pennsylvania, have invented certain Improvements in Railway-Cars, of which the following is a specification.

Our invention relates to certain improvements in metallic freight cars of the closed or "box" type.

One object of the invention is to construct the car so that the elements forming the car can be made from sheet metal pressed into shape.

15 A further object of the invention is to provide a car in which the side plates and end plates are reinforced by a series of corrugations formed between the uprights or posts, and to locate the posts on the interior 20 of the car so that they form a lining support and so that the sides of the car will be substantially flush with the exception of the ends.

25 A still further object of the invention is to strengthen the ends of the car by providing a series of double posts, which reinforce the ends to such an extent as to prevent the ends from bulging, due to the shifting of the load.

30 Another object of the invention is to design the roof of the car so that a substantial skeleton frame can be used to take the strains while a comparatively light material is used for the body.

35 Still another object of the invention is to design the interior of the car so that light linings of wood, or other material will be properly supported and can be readily attached or detached intact, as desired.

40 There are still other objects of the invention which will be fully described hereinafter.

In the accompanying drawings:

45 Figure 1 is a side view of about three-fourths of a car, illustrating our invention, the door being detached in this instance and the wheels being shown by dotted lines;

Fig. 2 is a plan view of the car illustrated in Fig. 1;

50 Fig. 3 is an end view;

Fig. 4 is a side view of a car door detached;

Fig. 5 is a sectional plan view of one end of a car;

Fig. 6 is a transverse sectional view on the line *a—a*, Fig. 2;

Fig. 6^a is a transverse sectional view on the line *g—g*, Fig. 2;

Fig. 7 is a vertical sectional view on the line *b—b*, Fig. 5, illustrating the end of a car;

Fig. 8 is a vertical sectional view of the side of a car on the line *c—c*, Fig. 1;

Fig. 9 is a vertical sectional view on the line *d—d*, Fig. 1;

Fig. 10 is an enlarged vertical sectional view on the line *e—e*, Fig. 1, through the doorway and showing the door in the closed position;

Fig. 11 is an enlarged vertical sectional view on the line *a—a*, Fig. 2, showing the inner and the outer posts in section;

Fig. 12 is a sectional view of the upper portion of a car at one end on the line *f—f*, Fig. 2;

Fig. 13 is a detached perspective view of the two elements forming the posts at the side of a car;

Fig. 14 illustrates the two elements forming the posts at the end of a car;

Fig. 15 is a sectional plan view at the door openings, showing the door in the closed position;

Fig. 16 is a plan view of one corner of the roof;

Fig. 17 is an end view of one corner at the roof;

Fig. 18 is a side view of one corner at the roof;

Fig. 19 is a perspective view, showing the roof plates secured to the cornice plate;

Fig. 20 is a perspective view of one of the shaped end plates of the roof;

Fig. 21 is a perspective view of a portion of one of the roof cornice plates;

Fig. 22 is a perspective view of one of the corner braces;

Fig. 23 is a perspective view showing the skeleton roof frame;

Fig. 24 is a sectional perspective view of the upper portion of the car at one of the carlines;

Fig. 25 is a sectional view showing one method of fastening the wooden corner posts to the metal frame;

Fig. 26 is a detached perspective view of one of the posts, showing the upper and lower reinforcing sockets;

Fig. 27 is a perspective view of the upper post socket;

Fig. 28 is a perspective view of the lower post socket;

Fig. 29 is a sectional view showing the method of attaching the lower ends of the posts at the ends of the car;

Fig. 30 is a sectional perspective view at the upper end of one of the side posts, showing

10 the overhanging cornice strip;

Fig. 31 is a sectional perspective view of one of the cornice beams; and

15 Fig. 32 is a sectional perspective view of the cornice piece and a side plate at one side of the doorway.

In the first instance, it will be understood that the platform, or floor construction, and the end work of the car may be made in any suitable manner without departing from the 20 essential features of the invention, which relate solely to that part of a car above the supporting structure.

Referring to the drawings, 1, 1 are the longitudinal stringers made of angle plate 25 and extending from one end of the car to the other. 2 is the floor of the car and 3, 3 are the angular bumper plates, one located at each end of the car. The under framework of the car may consist of longitudinal 30 stringers of any shape, cross beams, and bolsters, to which the trucks are pivoted.

4, 4^a and 4^b are the side plates, which are continuous from one end 5 of the car to the center door opening 6 at each side. The 35 plates are preferably of different thicknesses, the plate 4 being the thickest plate and located at the lower portion of the car. The plate 4^a is less in thickness than the plate 4 and is located midway between the top and 40 bottom of the car, and the plate 4^b is still lighter and is located at the upper portion of the car. The lower edge of the plate 4^a overlaps the edge of the plate 4, and the lower edge of the plate 4^b overlaps the upper edge of the plate 4, the plates being secured together by a line of rivets, as shown 45 in Fig. 1. In the present instance, each of the plates has a series of longitudinal corrugations spaced a given distance apart and 50 these corrugations are on the inner sides of the plates and are discontinued at the posts so that each plate will have a flat portion 7 to which the posts 8 are secured. These posts 8 are made as clearly shown in Fig. 13, 55 and have flanges 9 with rivet holes therein and are located on the inner side of the plates.

10 is a series of flanged cap plates having a shallow central flat rib projecting about 60 in line with the rivet heads on either side thereof and are arranged in line with the inner posts 8. These plates project to the clearance line of the doors, thus adding materially to the strength of the posts. The 65 posts 8 are of a greater depth than the cor-

rugations of the side plates as shown in Fig. 5, and form the support for the lining boards 11, which are detachably or permanently secured to the inner walls of the car and may extend any distance from the floor, as desired. In the present instance, we have shown these lining boards extending about three-fourths of the height of the car, see Figs. 7, 8 and 9.

Battens 12 are secured to the lining 75 boards 11 and not only act as the means for holding the several longitudinal parts together, which are preferably tongued and grooved, but are of such a width that they fit against the side plates of the car between 80 the posts when the lining boards are resting against the posts. The ends 5 of the car are made of a series of plates 13, 13^a and 13^b, which are arranged transversely and extend from one side of the car to the other. These 85 plates may be of the same thickness or the plates 13^a and 13^b may be of less thickness than the plates 13 and they have a series of short longitudinal corrugations which project inward, as shown in Fig. 5, and are flat 90 at 14 so as to allow the outer and inner posts 15 and 16 to be secured rigidly to the plates. These posts are flanged and perforated and are firmly riveted to the plates, as illustrated in Fig. 3. The end posts 15 95 are made as illustrated in Fig. 14, the rib being tapered and preferably heavier near the lower end where the post is subjected to the greatest strain, while the post 16, Fig. 14, is preferably of the same depth throughout. Against the inner post 16 fit the end 100 lining boards 17, which are provided with battens 18, resting against the end plates between the posts, as clearly shown in Fig. 5. In order to finish the joint between the end 105 plates and the side plates, we preferably provide right angled corner pieces 19, which overlap both plates and within these corner 110 pieces are arranged the triangular wooden posts 20, as shown, or solid filler pieces 110 against which the ends of the lining boards 11 and 17 abut. These posts 20 may be made in two parts, as shown in Fig. 25, so as to be readily removed when the bolts are withdrawn.

In order to firmly secure the post 8 at the side of the car to the base and to the cornice girder 32, we form sockets of the type clearly shown in Figs 26, 27 and 28. The socket 55 at the base of the post has a vertical flange 56 and a base flange 57, the latter being secured to the sills of the car, and the former being secured to the flanges 9 of the post and to the side plates of the car, while the upper socket 58 is made as shown in Fig. 125 27, and is flanged and fits over the upper end of the post 8 and has an extension 59 which is riveted to the vertical portion of the cornice girder 32. This post is reinforced by these sockets and is firmly tied to 130

the longitudinal sill of the car at its lower end and to a longitudinal cornice girder at its upper end. The posts 15 and 16 at the ends of the car are secured to the brackets 5 48 which will be described hereafter and at the lower ends to the vertical portion of the bumper plate 3, as clearly shown in Fig. 29, the post 16 being offset at its lower end as shown in Fig. 14 to fit over the bumper 10 plate and the angle plate 3^a at the inside of the car.

By the above described construction, both 15 sides and the end of the car are rigid and substantial and are made entirely of pressed sheet metal. The corrugations are comparatively short and the plates all extend horizontally without splices and are reinforced at intervals by the posts, making an exceedingly substantial construction and obviating the necessity of diagonal brace members.

At the door openings, there are two flanged plates 21 and 22, vertically arranged and secured to the side plates and to the 25 reinforcing door strips 23. The plate 21 has an inturned flange 24 and the plate 22 has an outturned flange 25. The door 26 is made as shown in Fig. 4 and consists of three horizontally arranged plates, each 30 plate being corrugated longitudinally, the corrugations projecting inwardly and the plates being secured together and preferably of lighter gage than the plates 4, 4^a, and 4^b of the body of the car. On one edge of the 35 door is an angle plate 27 which has a projecting flange extending back of the inturned flange 24 of the plate 21 when the door is closed, and on the opposite side is a plate 28 having an inturned flange 29 40 which extends back of the flange 25 of the plate 22 when the door is closed. On the upper edge of the door is an angle plate 30 extending under the downturned flange 31 of the cornice plate 32, which extends 45 throughout the entire length of the car. The flanged portion 31 projects at a greater distance than the main portion so as to allow the door to slide freely when being opened or closed. The door is carried by 50 shoes or rollers 33 mounted on brackets 34 secured to the door and these rollers travel on the upper surface of the projecting flanged portion 31, as clearly illustrated in Fig. 10 so that when the door 55 is opened or closed the rollers 33 travel on the overhanging portion of the car frame and when the door is in the closed position it is entirely sealed against the weather. The rivets securing the plates to the angle 60 plates are back of the inside line of the door, avoiding the necessity of using countersunk rivets.

The projecting portion 31 of the cornice plate or girder 32 forms the outer guide for 65 the door and an angle plate 60 secured to

the cornice plate at this point acts as an inner guide for the door. This angle plate is on a line with the lower flange of the cornice plate so that the upper side plates 4^b are secured to this angle plate 60 as 70 clearly shown in Fig. 32.

Uprights 35, preferably of wood, are secured to the back of the flanged door strips 23 by transverse bolts 36, shown in Fig. 15, and the wooden lining with the reinforcing 75 battens and the corner wear strips 37 are secured to these posts by screws 38 so that, on removing the screws, the entire lining at the sides of the car can be detached and removed from the car, when desired. 80

At the lower edge of the door is an angle plate 39, which extends back of the brackets 40 spaced a given distance apart so as to engage the bottom of the door when it is opened and closed. 85

The roof of the car is constructed as shown in Figs. 1, 2, 6, 12 and 23, and consists of a quadrangular frame, a series of carlines extending across the frame at intervals and corrugated roof plates extending from side to side of the car and secured to the carlines and to the frame. 90

The end plates 45 are very substantially made and form, in fact, end girders for the car. They are shaped from comparatively 95 thick plates and are flanged at one side, as at 47, and at each end, as at 47^a. The edge 46 of the plate is raised and is attached to the comparatively thin roof plates 42. Over this joint is placed the calking strip 49. 100 To the upper end of each post at the end of the car is secured a bracket 48, which extends under the girder plate 45 and a series of rivets attach the bracket, girder plate, the roof plate and the calking strip 105 together, as clearly shown in Fig. 12. The flange 47 of the girder plate 45 overlaps the upper end plate 13^b and posts 15 and the flanges 47^a overlap the upper portion 32^a 110 of the cornice girder and the cornice girder and the girder plates are securely fastened to reinforcing corner plates 54 of the shape clearly illustrated in Fig. 22. This construction makes an exceedingly substantial frame for supporting the roof and also adds 115 materially to the strength of the car body.

Extending from one side of the car to the other preferably at the several side posts are the roof carlines 41, made as clearly 120 shown in Figs. 12 and 24. These carlines, in the present instance, are flat at the top and the roof plates 42 extend from one carline to the other and are ribbed or corrugated between the carlines as clearly shown in Fig. 2, and where the roof plates overlap at the carline a calking strip 43 is placed and the rivets extend through the several parts, securing the roof plates to the carlines. The carlines are tapered at the center more than at the edges and the 130

flanges are turned up, as shown at 44, Fig. 12, so as not only to add strength to the structure, but also to carry any water, which may leak through the joint, to one side of the car. The flanged portion of the roof plates is shaped to form channels to permit the water to escape outside of the car, as clearly shown in Fig. 24. Each roof plate is of a length to extend from one side of the car to the other and of a width to extend from one carline to another and the ends of the plates are flanged so as to extend over the portion 32^a of the cornice girder. Each plate has a central longitudinal corrugation 50, extending substantially the full width of the plate and on account of its location on the highest point of the roof, comparatively short length, and consequent stiffness, it forms a strong but light support for one end of the series of transverse strengthening ribs or corrugations 51 on either side thereof which originate close to the longitudinal rib and extend to the edges of the car. Without this central rib these transverse ribs would have to extend from side to side of the car and, consequently, would have less strength.

In some instances, it is necessary to provide ventilation throughout the entire length of the car at the roof and we preferably mount washers 63 on the rivets which secure the flanges of the roof plates to the vertical portion of the cornice girders, leaving an open ventilating space between the washers and the flanges of the roof plates, preventing rain water, sparks, etc., from entering the car.

52 is an ordinary roof walk, consisting of a series of boards placed longitudinally and resting on brackets 53 projecting from the roof of the car at the carline. The side cap plates 10, which form part of the posts, are of an even width throughout, with the exception of the posts in line with the bolsters 55 and these plates are of a greater width at the base than the others so as to increase the strength of the fastening between the car body and the bolster, although, in some instances, these plates may be of an even width throughout, if desired.

It will be noticed that the side plates 4^b stop short of the flanged cornice girders 32 so that the space formed by the cap plate 10 is open to the interior of the car at the top and is open to the atmosphere at the bottom. Thus a vent is provided for the upper portion of the car. The car is provided with the standard fittings and these fittings have not been described and, in some cases, are not shown in the drawings, as they form no part of the present invention.

By the above construction, it will be seen that a car made according to our construction has a body portion made entirely of pressed sheet metal, preferably steel, the

side posts being practically on the inside of the car, while the end posts are double and are partly on the outside and partly on the inside of the car. Both posts are hollow, being made of pressed plates flanged and of a depth governed by the size and character of the car.

The side plates, as before mentioned, are made in three sections and the heavier sections are at the base where the pressure is heaviest and the light sections are at the top but, in some instances, the plates may be of the same thickness throughout, or the bottom section and the intermediate section may be of the same thickness and the top section may be made of a lighter plate.

While we have illustrated the sides as consisting of three longitudinal plates, a single plate, two or more than two plates may be used without departing from the essential features of the invention.

It may be noticed that the end girder plates 45 are pressed out at 61 to fit over the ends of the outside posts 15, thus adding materially to the rigidity of the posts and the side cornice girders 32 are pressed out at 62 to receive the upper ends of the cap plates 10 for the same purpose. The projecting portion 31 of the cornice girder 32 at one end is continuous with the lower flange of the body of the girder, but at the opposite end it is open for the insertion of the door as clearly shown in Fig. 23.

While we have illustrated the carlines as located on a line with the side posts it will be understood that they may be located at different points throughout the length of the car, depending materially upon the weight of the roof and the character of the car.

The wooden lining of the car is made so that it can be readily detached in whole sections without being torn apart in order that it may be readily repaired, or when it is desired to repair or paint the interior of the metal body, and the sections of the lining can be of any height and thickness desired and may be secured by through bolts or other fastenings. The lining has an inclined cap plate 64, which is shaped so as to prevent grain, or other material from entering the space between the lining and the metal body of the car.

We claim:

1. The combination of a freight car having sides and ends and a roof, the sides being made of a series of plates corrugated lengthwise, one plate being arranged above another and secured thereto; a series of posts spaced apart and made of bent sheet metal, the posts having flanges at each side and the plates at the posts being free of corrugations so that the flat flanges of the posts can be secured to the flat portions of the plates; and cap plates located on the outside of the

car in line with the posts and secured thereto and to the side plates.

2. The combination in a freight car, of a series of side plates placed one above another, the edges of one plate being secured to the edges of another plate, the upper plates overlapping the lower plates; a cornice plate extending throughout the length of the car and overlapping the top plate; a series of inside posts; an outside cap plate in line with the posts; and a roof structure secured to the cornice plate.

3. The combination in a car, of metallic side plates having short longitudinal corrugations spaced apart forming flat sections; a side post made of flanged and shaped plates and secured to the flat portions of the side plates; an outside cap plate slightly bent to form a longitudinal vent space, the cap plate being secured to the flat portions of the side plates in line with the posts; a cornice plate extending longitudinally of the car at the roof and overlapping the upper side plate, said upper side plate and post stopping short of the cornice plate and forming a vent opening communicating with the vent passage in the cap plate, said cap plate being open to the atmosphere at the bottom.

4. A freight car having an end consisting of plates corrugated horizontally, the corrugations being spaced apart by flat sections; and inner and outer vertical posts secured to the plates at the flat portions.

5. The combination in a freight car, of an end made of a series of plates, one located above another, and secured together, each plate having a series of short horizontal corrugations spaced apart by flat sections; and vertical posts extending the full height of the car, the post on the inside being of the same depth throughout and flanged, the post on the outside having a tapered rib extending a greater distance at the bottom than at a point near the top, the two posts being secured at their flanges to the flat portions of the plates.

6. The combination of a series of longitudinally arranged plates at the sides of a car, said plates having a series of spaced corrugations and having flat portions at intervals; internal flanged posts secured to the flat portions of the plates and external cap plates secured to the outside of the plates in line with the posts; a series of end plates having corrugations separated by flat portions; inner and outer posts secured to the plates at the flat portions; and corner plates secured to the side plates and to the end plates.

60 7. The combination in a freight car, of sides made of a series of plates arranged longitudinally and having short corrugations spaced by flat portions; vertical posts secured to the plates at the flat portions; horizontal end plates having short corrugations spaced by flat portions; inside and outside vertical posts secured to said plates; a cornice plate extending the full length of the car and overlapping the upper side plates; a heavy end roof plate overlapping the ends of the car; roof plates extending across the car and overlapping the side cornice and attached to the end plates; and carlines supporting the roof structure.

70 8. The combination in a freight car, of side plates and end plates; vertical internal posts spaced apart and secured to the side plates and end plates, said plates being corrugated between the posts, the corrugations projecting inwardly; lining boards resting against the posts and having battens between the posts resting against the corrugations of the plates, said lining boards being detachably secured in position.

85 9. The combination in a freight car, of side plates and end plates; vertical internal posts spaced apart and secured to the side plates and end plates, said plates being corrugated between the posts, the corrugations projecting inwardly; lining boards resting 90 against the posts and having battens between the posts resting against the corrugations of the plates; vertical door posts back of the door strips and secured to said strips, the lining being detachably secured to the said 95 posts; and bolts securing the lining boards to the side plates of the cars at the battens.

100 10. The combination of a freight car of the "box" type having corrugated side and end plates; a series of posts located on the interior of the car, said posts being of a greater depth than the corrugations of the plates; lining boards located on the inside of the car and bearing against the posts and having battens located between the posts; 105 means for detachably securing the lining boards to the body of the car; and an inclined board at the upper end of the lining sections extending to and fitting the corrugated plates at the sides and ends of the car. 110

115 11. The combination of a freight car of the "box" type having corrugated side and end plates; posts located within the body of the car to which the corrugated plates are secured, said posts being of a greater 115 depth than the corrugations of the plates; lining boards located on the inside of the car and bearing against the posts and having battens located between the posts; means for detachably securing the lining 120 boards to the body of the car; an inclined board at the upper end of the lining sections extending to and fitting the corrugated plates at the sides and ends of the car; triangular corner posts at each corner of 125 the car against which the ends and sides of the end sections abut; doors; and a post at each door to which the lining is secured so that, on removing the fastening devices, the lining can be detached from the car body. 130

12. The combination in a metal box car, of a series of vertical hollow posts made of sheet metal; a series of side plates secured to the posts; hollow cap plates mounted on the outside of the car at the posts; and a roof structure extending over the side plates of the car, the space formed by the cap plates being open at the top and bottom. 45
13. The combination in a box car, of a base frame; vertical posts; a cornice structure consisting of longitudinal flanged girder plates; transverse flanged girder plates at the ends of said cornice plates; said cornice and girder plates being shaped at intervals to receive the upper ends of the posts. 50
14. A frame for the upper portion of a car consisting of end girder plates on each end of the car, and a cornice girder at each side of the car, the said end girder plates being firmly secured to the cornice plates, both of said girder plates having depending flanges, the flanges being pressed out to receive the ends of the posts forming part of the car structure. 55
15. The combination in a metal car of a series of posts on the inner side of the car at the sides and ends; plates attached to the posts; posts on the outside of the car at each end; cap plates in line with the side posts on the outside of the car; and a frame consisting of end girder plates and side cornice plates flanged to extend over the upper edges of the sides and ends of the car; the flanges being pressed out so as to extend over the ends of the outside posts and cap plates. 60
16. The combination in a car of inside posts at the sides of the car; side plates secured to the posts; cap plates mounted on the outside of the side plates in line with the posts and secured thereto; a flanged girder plate, the lower flange of said plate extending over the upper end of the side plates and pressed out and extending over the end of the cap plate. 65
17. The combination in a box car of a body portion with a flanged cornice girder extending the length of the car, the flange of said girder being extended over the door of the car and forming the upper guide for the car door; with a plate secured to the side cornice girder back of the extended flange and in line with the lower flange of the main portion of the girder and acting as the inner guide for the door and to which the said side plates are attached. 70
18. The combination of a cornice girder for a car body having a flange at its lower edge, an integral portion of said flange projecting beyond the body of the flange at the doorway and forming a guide for the door. 75
19. The combination in a metal car of vertical posts; a cornice girder; carlines; side plates; and roof plates; vertical cap plates on the outside of the car in line with the posts; with means for securing the several elements together at the cornice girder. 80
20. The combination of a metallic freight car having a door opening at each side; corrugated side plates extending longitudinally of the car; vertical posts arranged at intervals and secured to the side plates; a cornice girder extending throughout the length of the car and having a flange extending over the side plates of the car, the flange above the door opening extending a greater distance outward than the flange at the balance of the cornice girder. 85

In testimony whereof, we have signed our names to this specification, in the presence of two subscribing witnesses.

JOHN S. WORTH.
CHARLES BRECHT.
